UNITED STATES PATENT OFFICE.

GEORGE S. VAN PELT, OF NEW YORK, N. Y., ASSIGNOR TO WILLIAM C. HOWARD, OF SAME PLACE.

DESIGN FOR A WATER-BAG.

SPECIFICATION forming part of Design No. 33,215, dated September 18, 1900.

Application filed July 17, 1900. Serial No. 23,979. Term of patent 14 years.

To all whom it may concern:

Be it known that I, GEORGE S. VAN PELT, a citizen of the United States, residing at New York, in the borough of Manhattan, county and State of New York, have invented and produced a certain new and original Design for Water-Bags, fully described and represented in the following specification and the accompanying drawing, forming a part of the same.

This invention relates to a new and original design for a water-bag; and the invention consists in a peculiar shape or configuration of the same, with the opposite sides or edges curved inwardly, substantially as shown in the accompanying drawing, in which—

C is the water-bag, the opposite sides or edges of the body thereof being formed with inward curves *a*, which inwardly-curved shape forms the leading feature of the design.

What I claim is—

The design for a water-bag, substantially as shown and described.

In testimony whereof I have hereunto set my hand, this 12th day of July, 1900, in the presence of two subscribing witnesses.

GEORGE S. VAN PELT.
